US00D745560S

(12) **United States Design Patent**
Lee

(10) **Patent No.:** US D745,560 S
(45) **Date of Patent:** ** Dec. 15, 2015

(54) **DISPLAY SCREEN OR PORTION THEREOF
WITH ICON**

(71) Applicant: **Samsung Electronics Co., Ltd.**,
Suwon-si (KR)

(72) Inventor: **Seung-Myung Lee**, Seoul (KR)

(73) Assignee: **Samsung Electronics Co., Ltd.**,
Suwon-si (KR)

(**) Term: **14 Years**

(21) Appl. No.: **29/476,203**

(22) Filed: **Dec. 12, 2013**

(30) **Foreign Application Priority Data**

Sep. 3, 2013 (KR) 30-2013-0045232

(51) **LOC (10) Cl.** 14-04

(52) **U.S. Cl.**

USPC **D14/492**

(57) **CLAIM**

The ornamental design for a display screen or portion thereof with icon, as shown and described.

DESCRIPTION

FIG. 1 is a front view of a display screen or portion thereof with icon, showing my new design; and,

FIG. 2 is a front view of a display screen or portion thereof with icon, showing an alternative embodiment of the new design.

The dot-dash broken lines illustrating portions of the display screen are included for the purpose of illustrating environmental structure and form no part of the claimed design.

1 Claim, 1 Drawing Sheet

FIG. 1

FIG. 2
